(57) **CLAIM**

The ornamental design for a computer mouse skin, as shown
and described.

DESCRIPTION

FIG. 1 is a front isometric view of a computer mouse skin in
accordance with the new design;

FIG. 2 is a top plan view thereof;

FIG. 3 is a right side elevation view thereof;

FIG. 4 is a front view thereof;

FIG. 5 is a rear view thereof;

FIG. 6 is an alternate top plan view thereof; and,

FIG. 7 is another alternate top plan view thereof.

Broken lines shown in the drawings are directed to environment
only and form no part of the claimed design.
